UNITED STATES PATENT OFFICE.

HENRY L. PLUMMER, OF PETERSBURG, VIRGINIA, ASSIGNOR TO INDEPENDENT TRUNK AND BAG COMPANY, OF PETERSBURG, VIRGINIA, A CORPORATION OF VIRGINIA.

MACHINE FOR CUTTING AND PREPARING DRESS-SUIT-CASE BODY-BLANKS.

1,340,558.

Specification of Letters Patent. Patented May 18, 1920.

Application filed September 9, 1919. Serial No. 322,764.

To all whom it may concern:

Be it known that I, HENRY L. PLUMMER, a citizen of the United States, residing at Petersburg, in the county of Dinwiddie and State of Virginia, have invented certain new and useful Improvements in Machines for Cutting and Preparing Dress-Suit-Case Body-Blanks; and I do hereby declare the following to be a full, clear, and exact description of the invention, such as will enable others skilled in the art to which it pertains to make and use the same.

This invention relates to improvements in machines for cutting, punching and creasing paper blanks or sheets, and especially to a machine designed for preparing the body blanks of dress suit cases.

Some types of dress-suit cases are provided with a substantial card board body or inner liner which is ordinarily cut to approximately a given size and contour, and the present invention provides a machine for treating this previously cut blank for forming the body so as to facilitate the bending of the main panels thereof to form a side and longitudinal parallel components of the body.

In the present case the type of suit case for which the blanks are cut is provided with a cardboard sheet or body member which is lined previously to be finally cut, punched and creased on one side with a suitable trimming and finishing sheet of material, and the present invention has for its object to simultaneously cut the trimming sheet to the desired outline and to punch and crease the principal or body forming card along such lines and at such positions as will facilitate the folding of the several panel and edge or corner forming areas, an especial object of the invention being to provide a machine that will operate effectually and which will permit the rapid insertion and proper registration of the blank to be cut and which will produce accurately cut and completely finished blanks.

With the above and other objects in view as will be readily manifest to those skilled in the art, the invention consists of the construction, the combination, and in details and arrangement of the parts as more particularly described hereinafter relative to the embodiment of the invention disclosed in the accompanying drawings, wherein:

Figure 1 is a plan view of the body blank

with its cover sheet previously to being cut in the machine forming the subject matter of the present application.

Fig. 2 is a plan view of the completed blank. 60

Fig. 3 is a perspective view of the main or body blank folded ready to be installed or assembled in the process of manufacturing the box of the dress suit case.

Fig. 4 is a vertical longitudinal section 65 through an embodiment of the invention.

Fig. 5 is a plan view of the lower die, the pins being shown in section on line 5—5 of Fig. 4.

Fig. 6 is a detail plan view in section of 70 the guide pins, the punch and the creasing dies.

Fig. 7 is an enlarged detail view of the corrugating and creasing dies.

Fig. 8 is a plan view of a fragment of the 75 lower die showing the guide pins in section and indicating in dotted lines the position of an adjusted blank.

In Fig. 1 the main body forming card of the dress suit box is indicated at C, it having been cut to the required size and given the desired formation by any suitable apparatus and method, and being indicated as having a pair of parallel edges V-notched at 2 to facilitate the folding of the blank 85 C to the position shown in Fig. 3.

The edges of the V-notches meet to form the joint 4 between the edge flanges 5.

The corners of the body blank are also peculiarly cut away or notched out, as at 6, to 90 produce the desired finish of the corners of the parallel side members 6—6 in Fig. 3.

In the method that I follow in the manufacture of this type of box there is applied to the back of the blank or card C in Fig. 95 1 a suitable strip or sheet of paper or other suitable material of the desired properties, this being indicated as forming a binder B of generally longer area than the card or blank C, as plainly shown in Fig. 1, it being 100 notched at 7—7 complementary to the notches 2 of the card so as to facilitate folding and eliminate any crinkling at the inwardly folded joints 4.

My present improvements are designed to 105 facilitate the manufacture or production of the completed blank as shown in Fig. 2 in which the card C is shown as deeply scored or corrugated along parallel lines 8 extending longitudinally of the blank and is simi- 110

larly corrugated along parallel lines 9 near the edge and perpendicular to the lines 8.

Further, the edges of the card C are grooved and are score lined along lines 5 10—10 parallel to the corrugations 9—9, the deep corrugations 8 and 9 facilitating the bending of the card with the respective portions at right angles to each other, such deep corrugations being clearly shown in 10 Fig. 7, while the lesser score lines facilitate the bending of the lips 11—11 in Fig. 3, these lips being bent over but a relatively slight degree from the plane of the side panels 6—6.

15 For the purpose of enabling the blanks to be rapidly inserted in a machine and punched, cut and creased in one operation, I have provided a machine including any suitable platen or table, indicated at T on which 20 is arranged a lower die structure 13 of any suitable form of construction and above the die 13 there is arranged a reciprocating head 14 on which is arranged an upper or male die structure 15 complementary to the die 13.

25 The lower die is shown as provided with apertures 16 here shown as formed in bushings 17, preferably of hard material, to serve as counter cutters coöperating with punches 18 forming a part of the upper die 15. The 30 punches at the rear of the head 14 are shown as provided with eccentrically arranged and downwardly extending guide pins 19, the pins and punches being designed to pass downwardly into the openings 16.

35 When the punch head 14 ascends to the uppermost position of the punch head the pins 19 are still extended into the apertures 16 in the die 13 and the operator has but to push the blank B—C over the lower die 13 40 until the V-notches 2—2 at the opposite edge encounter the guide pins 19, whereupon the latter will serve to automatically guide the blank to its proper position upon the lower die 13.

45 Thereupon, while the upper die 15 attached to the punch head 14 is caused to move downwardly, the punches 18 will pass through the blank to be punched and enter the holes 16. Immediately following or 50 approximately at the same time of the operation of the punches 18 corrugating blades 20 forming a part of the upper die 15 will engage the upper surface of the inserted card or blank and depress or corrugate the same by forcing it downwardly into complementary channels or grooves 21 formed to register therewith in the upper face of the die 13.

Following the corrugating step closely, 60 suitable creasing dies or blades 22 forming a part of the upper die 15 engage the upper face of the card being operated upon and indents or compresses the card to a suitable degree, thus forming the marginal creases 65 10—10 in Fig. 2.

As the creases 10—10 need not be so deep as the corrugations 20 it is not necessary to provide complementary channels or grooves in the face of the die 13 to match the compression device 22.

70 While the above described operation is proceeding knives 23 forming a part of the upper die 15 are effective to cut away the covers of the binding strip or sheet B to the outline indicated at 25, Fig. 2, and acting 75 in opposition to these knives I prefer to employ wooden or other soft material blocks 26 suitably connected to the die 13 to take the impression of the cutter edges and thereby protect the same against injury.

80 These blocks 26 are shown in Fig. 5 as being removable and held in place by clamps 27 so that as the blocks become unduly worn they may be disconnected and others inserted in their stead.

85 After the above described punching, corrugating and creasing steps have been completed the plunger head 14 ascends and in order to eject or strip the card B—C from the plungers any suitable stripping device may 90 be employed, it being shown as comprising, in the present case, a plate 28 mounted on the lower ends of the carrying pins 29 which are slidably mounted in the punch head 14 and are automatically pressed downwardly 95 by ejector springs 30 surrounding the pins 29. In the uppermost position of the plunger head 14 the plate 28 is sufficiently elevated above the face of the die 13 to enable the operator to readily insert the card 100 B—C to be punched into position, this being guided as in the manner above described by the guide pins to their proper location.

105 What I claim as new and desire to secure by Letters Patent, is:

1. In an apparatus for preparing blanks for boxes, the combination of a supporting table, male and female die mechanism including guide means to facilitate the location of the blank, punching devices to punch the inserted card, corrugating devices to corrugate the blank, and creasing devices to crease the blank, all in given organization and operating substantially simultaneously at one operation of the mechanism.

110 2. In an apparatus for preparing blanks for boxes, the combination of a supporting table, male and female die mechanism including guide means to facilitate the location of the blank, punching devices to punch the inserted card, corrugating devices to corrugate the blank, and creasing devices to crease the blank, all in given organization and operating substantially simultaneously at one operation of the mechanism, said 115 guide means being attached to the punching means.

120 3. In an apparatus for preparing blanks for boxes, the combination of a supporting table, male and female die mechanism in- 125

cluding guide means to facilitate the location of the blank, punching devices to punch the inserted card, corrugating devices to corrugate the blank, and creasing devices to crease the blank, all in given organization and operating substantially simultaneously at one operation of the mechanism, said guide means being attached to the punching means and designed to engage an inserted blank to be operated upon while the die members are in relatively separated position.

4. In an apparatus for preparing blanks for boxes, a stationary die having an operative face provided with channels or grooves and punch receiving means; and a movable die member including means for corrugating an inserted blank by depressing the same in the said channels in the stationary die, and punching means designed to enter the punch receiving apertures, said punching means provided with guide pins extending into the punch receiving apertures when the die members are fully separated and whereby an inserted blank is directed to its position.

5. In an apparatus for preparing blanks for boxes, relatively movable male and female die members for punching, corrugating, creasing and trimming the blank to its final condition to be folded into box form, and guide rods carried by said male punching members and reciprocating in said female punching members.

35 6. In an apparatus for preparing blanks for boxes, relatively movable male and female die members for punching, corrugating, creasing and trimming the blank to its final condition to be folded into box form, and guide means carried by the punching means to facilitate the positioning of the blank to be operated upon between the separated dies.

7. In an apparatus for preparing blanks for boxes and trimming the cover sheet of the blanks, a pair of relatively movable dies one of which is provided with grooves and

the other with projections complementary to said grooves for the purpose of corrugating an inserted blank, means for trimming 50 the corners of the cover of the blank, and means for positioning said blank relatively to said dies.

8. In an apparatus for preparing blanks for boxes and trimming the cover sheet of 55 the blanks, a pair of relatively movable dies one of which is provided with grooves and the other with projections complementary to said grooves for the purpose of corrugating an inserted blank, and means for trimming 60 the corners of the cover of the blank, and punching means carrying guide devices to facilitate the positioning of an inserted blank between the open dies, and means for stripping the punched blank from the 65 punches.

9. In a machine for completing blanks for boxes, a female die, a male die with plungers to enter the former and perforate an inserted blank, and guide pins arranged 70 on the ends of the plungers and designed to enter the apertures of the lower guide to guide an inserted blank to its proper position.

10. In a machine for completing box 75 blanks having preliminarily cut V-shaped guide notches, a female die, a male die with plungers to enter the former and perforate an inserted blank, and guide pins arranged 80 on the ends of the plungers and designed to enter the apertures of the lower guide to guide an inserted blank to its proper position by engagement with the V-shaped notches of the blank.

11. In apparatus for cutting blanks, a 85 platen or table member, a cutter head cooperative with the table member or platen and having cutters arranged thereon, and removable impression taking blocks in the table or lower member to take the wear due 90 to the operation of the cutter members.

In testimony whereof I affix my signature.

HENRY L. PLUMMER.
